UNITED STATES PATENT OFFICE.

DAVID A. WALLING, OF MERRYVILLE, LOUISIANA.

ELECTRIC-LAMP SOCKET.

1,231,819.

Specification of Letters Patent.

Patented July 3, 1917.

Application filed January 29, 1917. Serial No. 145,251.

To all whom it may concern:

Be it known that I, DAVID A. WALLING, a citizen of the United States, residing at Merryville, in the parish of Beauregard, 5 State of Louisiana, have invented a new and useful Electric-Lamp Socket; and I do hereby declare the following to be a full, clear, and exact description of the invention, such as will enable others skilled in the art to 10 which it appertains to make and use the same.

This invention relates to a new and useful electric lamp socket and a switch therein, and one of the objects of the invention 15 is to provide a device of this kind which is simple, efficient, and may be inexpensively manufactured.

A further object of the invention is to provide a lamp socket comprising an outer 20 metallic shell and an innermost porcelain core, there being insulating means therebetween, whereby the electrical connection between the lamp and the source of supply may be insulated from the outer shell.

25 A further object of the invention is to provide diametrically oppositely disposed electrical conductors carried by the porcelain core and provided with a contact ring spirally arranged, to be engaged by the 30 threads of the screw end of the lamp, there being a switch connected to one side of the line while one of the conductors is connected to the other side, in combination with means to throw the switch in contact with 35 the terminal contact of the screw of the lamp, so as to close the circuit.

In practical fields, the details of construction may necessitate alterations falling within the scope of what is claimed.

40 The invention comprises further features and combination of parts, as hereinafter set forth, shown in the drawings and claimed.

In the drawings:—

Figure 1 is a view in perspective of the 45 improved lamp socket, constructed in accordance with the invention, showing a portion of the lamp connected thereto.

Fig. 2 is a view in perspective, showing the outer shell removed.

50 Fig. 3 illustrates collective view of the several parts of the lamp socket excepting the outer shell disassembled.

Fig. 4 illustrates views of the several 55 parts of the core, one of the parts being separated from the others.

Fig. 5 is a vertical sectional view on line 5—5 of Fig. 1.

Fig. 6 illustrates collective views of the two parts of the outer metallic shell.

Referring more especially to the drawings, 1 designates the outer shell of the 60 socket, which shell consists of the two sections 2 and 3, each semicircular in cross section. Each section has a semi-spherical 65 globular end 4, and the opposite end which is provided with a reduced portion 5. It is to be noted that the marginal edge portion of the section 2 overlaps the marginal edge portion of the section 3, which edge portion of the section 2 is provided with lugs 70 to engage the apertures 7 of the marginal edge portion of the section 3, thereby holding the two sections together. Arranged on the interior of the outer metallic shell is an insulating shell 8, of any suitable material, 75 preferably fiber, which consists of the two sections 9 and 10. The section 10 is preferably semi-spherical in shape, to correspond to the spherical globular shaped end of the outer shell, while the section 9 corresponds 80 with and fits the shape of the body portion of the outer shell. In fact, one end of the insulating shell is reduced to correspond with the reduced ends of the two sections of the outer shell. A porcelain core 11, consisting 85 of the two sections 12 and 13, is arranged within the insulating shell, so that the section 13 will engage the interior surface of the semi-spherical globular insulating cap section 10, while the section 12 of the core 90 will fit the interior of the enlarged cylindrical part of the insulating shell 8. The section 12 of the core comprises the two parts 95 14 and 15, which are semi-circular in cross section. The flat face of the part 14 is provided with two grooves 16 and 17, the grooves 16 extending longitudinally the full length of said flat face, while the groove 17 extends substantially half the length of said flat face. The bottoms of the grooves 16 and 100 17 are provided with recesses 18. The part 15 of the section 12 of the core has its flat face provided with grooves 19 and 20 (the bottoms of which have recesses 21) to correspond and register with the grooves 16 and 105 17, when the two parts 14 and 15 of the section 12 of the core have their flat faces engaging each other. Arranged in said grooves 16 and 17, and 19 and 20, are conductor strips or members 22 and 23, the end 110

portions 24 of which are bent, in order to engage the inner surface of the reduced end of the insulating shell. It is to be noted that said conductor strips or members are diametrically oppositely disposed, and soldered as shown at 25 to the extremity of one of the end portions 24 is a ring 26, and at a point diametrically opposite the soldered connection, the ring is severed, and the two ends 10 27 and 28 are disposed off set from each other and soldered adjacent the extremity of the other end portion 24, so as to dispose the ring spirally, or in other words, screw threadlike, in order to be engaged by the 15 threads of the screw end 29 of the lamp 30. The flat face of the part 14 of the section 12, and the flat face of the part 15, are provided with diagonally disposed correspondingly substantially compound curved grooves 31 20 and 32, the bottoms of which have recesses 33. Arranged in said grooves 31 and 32, is a switch blade 34, which is constructed from a sheet of spring steel. This switch blade is provided with lugs 35 which engage said recesses 33 of said grooves 31 and 32, thereby preventing longitudinal slipping of the switch blade. The conductors 22 and 23 have lugs 36, which engage the recesses 18 and 21 of said grooves 16 and 17, and 19 and 20, thereby preventing longitudinal movement of said conductors. One end of each groove 31 and 32 is widened or enlarged in order to permit the end portion 37 of the switch blade to freely move. The section 13 35 of the core has its spherical face provided with grooves 38 and 39. The wires or leads 40 and 41 enter through the opening 42 of the core section 13, and then engage the grooves 38 and 39. The end of the lead or 40 wire 40 is connected to the hook 43 of the conductor 22, while the end of the lead or wire 41 is connected to the hook 44 at one end of the switch blade 34. A suitable key 45 extends through the outer shell, the insulating shell and through the two parts 14 45 15 of the core section 12, and the shank of said key has an enlargement 46, which engages the lateral enlargements 47 of the two grooves 31 and 32. It is to be noted that 50 when twisting the key in one direction, causing the enlargement 46 to ride or cam against the switch blade so as to cause the extremity of the end portion 37 to contact with the terminal contact 48 of the screw 55 end 29 of the lamp 30, thereby closing the electric circuit through the lamp. A reverse movement of the key will open the circuit.

The invention having been set forth, what 60 is claimed as new and useful, is:—

1. A lamp socket and switch therefor, comprising an outer metallic shell, an innermost porcelain core, an insulating shell between said core and the outer shell, a pair 55 of terminal conductors embedded in said

core and having their ends extending beyond the core, a spiral or screw ring connected to the extended ends of said terminal conductors, to be engaged by the threads of the screw end of a lamp, one of said conductor terminals being in circuit with a source of current supply, a switch blade embedded in said core and provided with a yieldable end, and being in circuit with said source of current supply, and a rockable key 75 having an enlargement to move said yieldable end of the switch blade in contact with a terminal contact of the screw end of said lamp.

2. A lamp socket and switch therefor, 80 comprising an outer metallic shell, and innermost porcelain core, an insulating shell between said core and the outer shell, a pair of terminal conductors embedded in said core and having their ends extending beyond the core, a spiral or screw ring connected to the extended ends of said terminal conductors, to be engaged by the threads of the screw end of the lamp, one of said conductor terminals being in circuit with source 90 of current supply, a switch blade embedded in said core and provided with a yieldable end, and being in circuit with said source of current supply, and a rockable key having an enlargement to move said yieldable end 95 of the switch blade in contact with a terminal contact of the screw end of said lamp, said conductor terminals and the switch blade having lugs embedding in said core to prevent longitudinal movement of the 100 said conductor terminals and the switch blade.

3. A lamp socket and switch therefor, comprising an outer metallic shell, and an innermost porcelain core, an insulating shell 105 between said core and the outer shell, said porcelain core comprising a cylindrical body section and a spherical cap section, said cylindrical body section consisting of two elongated parts semi-circular in cross section, the adjacent flat faces of said two parts having correspondingly arranged registering long and short grooves having adjoining recesses, the long grooves extending the full length of the flat faces of both parts 110 and the short groove substantially half the length of said flat faces, the adjacent faces of said parts having additional elongated obliquely arranged grooves having recesses, conductor terminal strips diametrically oppositely disposed and being embedded in said long and short grooves and having their corresponding ends extended beyond the core, said extended ends having a spiral or screw ring to be engaged by the threads 125 of the screw end of a lamp, said conductor terminals having lugs engaging the recesses of said long and short grooves, the conductor terminal of the long groove being in circuit with a source of current supply, a 130

switch blade in said oblique grooves and having lugs to engage recesses of said oblique grooves, said switch blade in circuit with the source of supply and having a yieldable end, and means to move the yieldable end into contact with the terminal contact of the screw of the lamp.

In testimony whereof I have signed my name to this specification in the presence of two subscribing witnesses.

DAVID A. WALLING.
